Primary Examiner — Brett Miller*(74) Attorney, Agent, or Firm* — Jeffrey A. Proehl; Woods, Fuller, Shultz & Smith, PC(57) **CLAIM**

The ornamental design for a portion control device for pets, as shown and described.

DESCRIPTION

FIG. 1 is a perspective view of the portion control device for pets of the present disclosure;

FIG. 2 is a top plan view of the portion control device for pets;

FIG. 3 is a bottom plan view of the portion control device for pets;

FIG. 4 is a front elevational view of the portion control device for pets;

FIG. 5 is a rear elevational view of the portion control device for pets;

FIG. 6 is a left side elevational view of the portion control device for pets; and,

FIG. 7 is a right side elevational view of the portion control device for pets.

The broken lines depict portions of the device that form no part of the claim.
